(57) **CLAIM**

The ornamental design for a headset with image capturing means, as shown and described.

DESCRIPTION

FIG. 1 is a rear perspective view of the invention.

FIG. 2 is a front perspective view of the invention.

FIG. 3 is a top perspective view of the invention.

FIG. 4 is a bottom plan view of the invention.

FIG. 5 is a right side perspective view of the invention.

FIG. 6 is a left side perspective view of the invention.

FIG. 7 is a rear elevation view of the invention; and,

FIG. 8 is a front elevation view of the invention.
